UNITED STATES PATENT OFFICE

2,446,317

PLUG FOR ELECTRIC CIRCUIT

Wilmer L. Wilshusen, Garden City, Kans.

Application March 27, 1945, Serial No. 585,147

1 Claim. (Cl. 173—361)

1

This invention relates to plugs for use in electric circuits and it is designed primarily for use in aircraft and in other places where the equipment is subjected to violent vibration. It has been found in practice that where connector plugs are employed under these conditions, they work loose and gradually rotate with the result that the wires connected to the plug become broken. An object of the present invention is to provide a connector plug which is so constructed as to be held against rotation so that it will function properly even though subjected to constant vibration.

A further object is to provide a connector plug which can be readily secured to parts already in use.

With the foregoing and other objects in view which will appear as the description proceeds, the invention consists of certain novel details of construction and combinations of parts herein-after more fully described and pointed out in the claim, it being understood that changes may be made in the construction and arrangement of parts without departing from the spirit of the invention as claimed.

In the accompanying drawing, the preferred form of the invention has been shown.

In said drawing:

Figure 1 is a side elevation of a connector plug constructed in accordance with the present invention, the same being shown positioned in a portion of an ordinary equipment case.

Figure 2 is a section on line 2—2 Fig. 1, the central stem being shown in plan.

Figure 3 is a face view of the retaining washer forming a part of the device.

Figure 4 is a face view of the insulating block.

Figure 5 is a face view of a portion of the equipment case showing the opening provided therein for the reception of the connector plug.

Figure 6 is a side view of the outer or shell portion of the plug.

Figure 7 is an end elevation thereof.

Figure 8 is a side elevation of the central stem of the plug, a portion being broken away.

Figure 9 is a section on line 9—9 Figure 8.

Referring to the figures by characters of reference, 1 designates a central stem which is cylindrical for the greater portion of its length and is provided at one end with the usual ball 2. From the other end, however, projects a flattened extension 3, there being a shoulder 4 formed by the stem 1 at the base of the extension 3 and another shoulder 5 at the base of the ball 2.

That portion of the stem 1 between the shoul-

2

ders 4 and 5 is cylindrical as before stated, and is fitted snugly within an insulating sleeve 6 which, in turn, is surrounded by a shell 7. A washer 8 of insulating material is interposed between the shoulder 5 and the adjoining ends of sleeve 6 and shell 7.

The shell 7 is provided with a disk-like head 9 at that end thereof remote from washer 8 and adjacent to this head the shell is enlarged as shown at 10. This enlarged portion is screw-threaded as at 11, but the threads are interrupted by one or more flat sides 12. A recess 13 is formed within the head 9 and is extended diametrically across the outer face thereof and this recess is proportioned to receive a block 14 of insulating material in which is formed an angular opening 15. This opening is proportioned to receive the flattened extension 3 which, when positioned therein, will prevent the central stem 1 from rotating within the shell 7 due to the fact that the engaged block 14 is held against rotation by the walls of the recess 13.

A retaining washer 16 is seated on the extension 3 and is held thereto by any suitable means, as by upsetting a portion of the extension so as to overlie a portion of the washer, as indicated at 17. With the washer thus held to the extension 3, the block 14, head 9, shell 7, sleeve 6 and stem 1 are all maintained fixed relative to each other.

The extension 3 can be provided with an integral pin 18 or the like at the end thereof to which a wire W can be joined as shown in Figures 1 and 2.

An opening 19 having one or more straight sides, is provided in the case of the equipment, a portion of which has been shown at 20. This opening is proportioned to receive the enlarged portion 10 of the shell 7 which will fit snugly therein and thus be held against rotation relative to the case. When this enlarged portion is thus seated in the opening the connecting plug can be securely fastened to the case by means of a nut 21 which is screwed onto the threaded portion 11 until a portion of the case is tightly gripped between said nut and the head 9.

With the parts thus assembled it will be apparent that it becomes impossible for the connecting plug to rotate relative to the case and, therefore, the possibility of the wire W becoming bent or twisted as a result of rotation due to vibration, is eliminated. Consequently, one of the hazards thus far experienced in the operation of airplanes, etc., is avoided.

What is claimed is:

The combination with a supporting structure

having an opening provided with a straight wall, of a connecting plug including a stem having a shoulder at one end and a flattened extension at its other end, an insulating sleeve on the stem, an insulating block fitted snugly on and held against rotation by the flattened extension, a shell fitted on the insulating sleeve having an enlarged end portion shaped to fit within and to be held against rotation by the walls of the opening in the supporting structure, a head integral with said enlarged end portion of the shell, having a recess constituting a seat for the block, thereby to hold the block in the head against relative rotation, said enlarged portion having screw threads, and a nut engaging the threaded

enlarged portion and cooperating with the head to grip the supporting structure.

WILMER L. WILSHUSEN.
